Attorney

UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPEWRITING MACHINE.

Application filed August 20, 1924. Serial No. 783,065.

To all whom it may concern:

Be it known that I, ALFRED G. F. KUROWSKI, a citizen of the United States, residing in Brooklyn Borough, in the county of Kings, city and State of New York, have invented certain new and useful Improvements in Typewriting Machines, of which the following is a specification.

This invention relates to typewriting machines, and more particularly to means for holding cards in position on the platen.

One of the features of this invention is the provision of a card-holder that will firmly hold the card and at the same time properly gage it in position on the platen.

Another feature is the provision of means for positioning said card-holder on the platen, and means for firmly holding it, which takes up a minimum of space. The card-holder is simple and economical to manufacture, and readily attached and detached from the machine.

Other features and advantages will hereinafter appear.

25 In the accompanying drawings,

Figure 1 is a front view of a typewriter platen with the present improvements applied thereto.

Figure 2 is a side view showing the means for positioning and securing the card-holder on the platen.

Figure 3 is a side view showing the card-holder in released position.

Figure 4 is a side view showing a card in position in the holder.

Figure 5 is a fragmentary front view partly in section.

Figure 6 is a diagrammatic perspective showing the curvature of the card-holder.

40 Referring to the drawings, a platen 10 is mounted on a shaft 11 journaled in frames 12. A hand-wheel 13 is fixed to each end of said shaft 11 for convenient rotation of said platen 10 to carry a work-sheet, illustrated as a card 14, around said platen between rear table 15 and front and rear pressure rolls 16 and 17, respectively, upwardly in front of the printing point indicated as a type-bar 18.

45 The present invention is concerned with means for holding said card 14 in a secure and proper position for typing. A card-holder 19 comprises a body-portion 20 extending the length of said platen 10 and terminating in downwardly-extending flanges

21, said body-portion 20 conforming to the curvature of the platen 10. Fastened to each of said flanges 21 is a pin 22. Said body-portion 20 is provided with beveled longitudinal edges 23 and 24 forming undercut portions 25 and 26, which leave spaces 27 and 28, between said beveled edges 23 and 24, respectively, and the surface of the platen 10 into either of which spaces is inserted the end of card 14. Said under-cut portions 25 and 26 create longitudinal shoulders 29 and 30, respectively, against either of which rests the end of card 14 to guide it in position on the platen. These shoulders 29 and 30 also serve to limit the introduction of said card 14. Formed on each of said longitudinal edges 23 and 24, at opposite ends of the body-portion 20, is a lug or side gage 31 which is provided with a flat edge 32 against which the side edge of said card 14 rests to guide it in proper position on the platen 10. These lugs 31 are also beveled to form cams so as to facilitate the movement of the holder 19 over the rear table 15 and feed-rolls 16 and 17. As will be apparent, each of the shoulders 29 and 30 forms an end gage for card 14 and each of the lugs 31 forms a side gage for said card 14.

50 To afford means to properly position the card-holder 19 on the platen and to securely hold the same thereon, use is made of the end plates 33 of platen 10 and the hubs 34 of said end plates 33. Secured to each of said end plates 33, at a point adjacent its circumference, is a guide-member 35 comprising upwardly-extending prongs 36 and 37, which prongs 36 and 37 extend upwardly to a point substantially flush with the surface of said platen 10. As will be seen from Figure 3, when the card-holder 19 is to be mounted in position on the platen 10, the side edges of said flanges 21 are brought into alignment with the inner edges of prongs 36 and 37, so that said flanges 21 may ride downwardly freely between said prongs 36 and 37, but said flanges 21 are snugly held therebetween to prevent the shifting of said holder 19 on the platen. Because of the flexibility of the holder 19, due to its slightly concave form, as shown in Figure 6, said holder tends to spring-off the platen 10, and means must be provided to securely hold the same thereon. This means, in the present invention, is shown as

a lever-member 38 pivoted on each of the end plates 33 of the platen 10 by means of a flat-headed screw 39. The flat head of said screw 39 serves as a guide to keep the lever 38 from lateral movement. The long arm 40 of said lever 38 terminates in a pawl 41 having an inclined face 42. The end of the short arm 43 of said lever 38 has formed thereon a lug 44. Surrounding this lug 44 is a compression spring 45, one end of which seats in a bore 46 formed in the hub 34 of end plate 33, and the other end of which seats on the shoulder 47 formed on the short arm 43 of the lever 38. Said long arm 40, it will be noted, is slightly curved, as indicated at 48, to dispose the pawl 41 in a plane to enable it to move free of the guide-member 35 and the flange 21. The short arm 43 is also curved outwardly, as indicated at 49, to permit the compression spring 45 to be seated in the hub 34. As will be apparent from Figure 3, the pawl 41 normally lies in the path of the downward movement of pin 22, so that, when the holder 19 is being pressed into position, said pin 22 rides downwardly over the inclined face 42 of pawl 41 and over the nose-portion 50 of said pawl 41 to the position shown in Figure 2. When it is desired to release said card-holder 19 from the platen 10 for performing other kinds of work, the lever 38 is rocked from its engagement with said pin by means of a knob 51 fastened to a lug 52 formed on the long arm 40 adjacent the pawl 41. When the holder 19 is in position on the platen 10, it will be noted that its flanged portions 21 and guide-members 35 are disposed in the same vertical plane, and the lever-member 38, with its associated parts, is so mounted as not to interfere with any of the parts of the machine disposed outside of the hub 34. By reason of this arrangement, a compact structure is provided. It will also be noted that the pivotal point, indicated by the screw 39 of the lever 38, is in alignment with the pin 22 of flange 21, when the holder 19 is in position, which, with the long arm 40, permits a greater leverage to more firmly secure the card-holder 19 in position.

Variations may be resorted to within the scope of the invention, and portions of the improvements may be used without others.

Having thus described my invention, I claim:

1. In a typewriting machine, the combination with a revoluble platen, of a card-holding attachment therefor, including a card-gripping body extending along the platen, the ends of said body terminating adjacent the ends of the platen, means adjacent the platen-ends and co-operating with the ends of said body for guiding the same to card-gripping position against the platen, and releasable detents carried by the platen and automatically engaging the ends of said

body as the latter is brought to card-gripping position, whereby to secure said attachment to the platen.

2. In a typewriting machine, the combination with a revoluble platen, of a card-holding attachment therefor, including a card-gripping body extending along the platen, and having the ends thereof directed so as to overlie the ends of the platen, guides fixed to the platen-ends for receiving the overlying ends of the body, whereby to guide said body to proper card-gripping relation against the platen, and releasable detents automatically engaging said overlying portions as the body is brought to card-gripping position, whereby the detents maintain the body-ends within the guides and said body against the platen.

3. In a typewriting machine, the combination with a revoluble platen, of a card-holding attachment therefor, including a body having parallel card-gripping edges at opposite sides thereof, the ends of the body being directed inwardly of the platen adjacent the ends thereof, guides for receiving the inwardly-directed ends, whereby to guide the body to card-gripping relation with the platen, lugs carried by said ends, and releasable detents automatically engaging said lugs as the body is brought to card-gripping position, whereby said body is held against the platen and said ends within the guides.

4. In a typewriting machine, the combination with a revoluble platen, of a card-holding attachment therefor, including a body having oppositely-disposed card-gripping edges, the ends of the body being turned at right angles, so as to overlie the ends of the platen, pins carried by the overlying ends, guides for the reception of the latter and preventing angular displacement of the body relative to the platen, and releasable detents associated with the ends of the platen, said detents having cam-portions lying in the path of said pins when said overlying ends are being inserted within the guides, the cams co-operating with the pins to move the detents out of the way, to permit said overlying ends to reach home position within the guides, said detents being effective to thereafter engage around said pins to hold the body against the platen and said overlying ends within the guides.

5. In a typewriting machine, the combination with a revoluble platen and work-piece guiding and feeding devices closely there-adjacent, of an attachment for holding cards against the platen, including a body extending along the platen, means associated with the ends of said body, whereby to maintain the latter in card-gripping relation against said platen, and gages for side-gaging a card, said gages having the outer portions thereof reduced in thickness to form tapered edges, said edges disposed substantially di-

agonally to the outer card-gripping edges of said body, whereby, when the platen is turned, said gages present narrow entering edges which gradually increase in width as said gages effect a lifting of said guiding and feeding devices, whereby to facilitate passage of said body around with the platen.

6. In a typewriting machine, in combination, a revoluble platen, a device for holding 10 a card on said platen, said device comprising a body-portion extending the length of said platen, a downwardly-extending flange formed at each end of said body-portion, and a pin carried by each of said flanges, 15 means to guide said device into or out of effective position, and means to hold said device in effective position on said platen, said holding means comprising a lever pivotally mounted at each end of said platen 20 and arranged to engage said pins to hold said device in effective position.

7. In a typewriting machine, in combination, a revoluble platen, a device for holding a card on said platen, said device comprising 25 a body-portion extending the length of said platen, a downwardly-extending flange at each end of said body-portion, a pin carried by each of said flanges, an end gage for said card carried by said body-portion, 30 and a side gage for said card formed on said body-portion, a guide-member to guide said device in position secured at each end of said platen, said member including a pair of prongs between 35 which said flanges are arranged to slide when said device is being moved into or out of effective position, and means for releasably holding said device in effective position, said means comprising a lever at each end of said platen pivotally mounted thereon, one end of 40 which terminates in a pawl and the other end of which carries a compression spring for normally pressing said pawl against said pin to hold the device in effective position.

8. In a typewriting machine, in combination, a revoluble platen, a device for holding a card on said platen, said device comprising a body-portion extending the length of said platen, a downwardly-extending flange at each end of said body-portion, and a pin carried by each of said flanges, a guide-member to guide said device in position secured at each end of said platen, said member including a pair of prongs between which said flanges are arranged to slide when 50 said device is being moved into or out of effective position, and means for releasably holding said device in effective position, said means comprising a lever at each end of said platen pivotally mounted thereon, one end of 55 which terminates in a pawl and the other end of which carries a spring for normally pressing said pawl against said pin to hold the device in effective position.

9. In a typewriting machine, in combination, a revoluble platen, a device for holding a card on said platen, said device comprising a body-portion extending the length of said platen, a downwardly-extending flange at each end of said body-portion, and a pin 60 carried by each of said flanges, a guide-member to guide said device in position secured at each end of said platen, said member including a pair of prongs between which said flanges are arranged to slide when 65 said device is being moved into or out of effective position, means for releasably holding said device in effective position, said means comprising a lever at each end of said platen pivotally mounted thereon, one end of 70 which terminates in a pawl and the other end of which carries a spring for normally pressing said pawl against said pin to hold the device in effective position, said member including a pair of prongs between which said flanges are arranged to slide when 75 said device is being moved into or out of effective position, means for releasably holding said device in effective position, said means comprising a lever at each end of said platen pivotally mounted thereon, one end of 80 which terminates in a pawl and the other end of which carries a spring for normally pressing said pawl against said pin to hold the device in effective position, and a knob to rock said lever upon its pivot to release said 85 device.

ALFRED G. F. KUROWSKI.
